UNITED STATES PATENT OFFICE.

WILLIAM JESSE HENRY FULLER, OF TORONTO, ONTARIO, CANADA.

GAS-LAMP.

1,212,621.

Specification of Letters Patent. Patented Jan. 16, 1917.

Application filed September 22, 1915, Serial No. 52,124. Renewed June 12, 1916. Serial No. 103,342.

To all whom it may concern:

Be it known that I, WILLIAM JESSE HENRY FULLER, a subject of the King of Great Britain, and resident of 12 Adelaide street west, 5 in the city of Toronto, county of York, Province of Ontario, in the Dominion of Canada, have invented certain new and useful Improvements in Gas-Lamps, of which the following is a specification.

10 The invention relates to improvements in gas lamps as described in the present specification and illustrated in the accompanying drawings that form part of the same.

15 The invention consists essentially of the novel construction and arrangement of parts whereby the gas is heated in its passage from the receiving chamber to the mixing and distributing chamber and in the novel means for lighting the several burners of 20 the lamp.

25 The objects of the invention are to facilitate combustion by heating the gas, to economize in the consumption of gas, to produce a gas lamp the parts of which are so arranged as not to cast a shadow on the globe thus producing a soft and even light, to facilitate the lighting of gas lamps and generally to provide a gas lamp which will be inexpensive to manufacture, durable and 30 efficient.

35 In the drawings, Figure 1 is a view of the lamp complete as it appears when suspended. Fig. 2 is a view of the lamp with the globe removed to show the arrangement of the parts. Fig. 3 is a vertical sectional view through the lamp. Fig. 4 is a plan view of the lamp with the globe removed. Fig. 5 is a perspective view of the cylindrical wire gauze used in the mixing chamber. Fig. 6 is a perspective detail of the 40 dish shaped wire gauze used in the mixing chamber.

45 Like numerals of reference indicate corresponding parts in each figure.

45 Referring to the drawings 1 is the mixing and distributing chamber being preferably of substantially inverted cup shape and having the inner wall of its open end 2 screw threaded for a portion of its height and the 50 openings 3 in the side wall thereof for the

insertion of gas supply pipes to the several burners.

4 is a receiving chamber formed by the cylindrical neck 5 projecting upwardly from the mixing chamber 1, said neck 5 55 having its inner wall converging inwardly adjacent to the lower end and forming the conical bottom 6 of the said chamber 4.

7 is a tube screw threaded into the upper end of the neck 5 and forming the suspending rod or stem of the lamp and also forming the connection between the receiving chamber and the source of gas supply.

8 is a metal casing suitably ornamented and inclosing the tube 7 to give a more attractive appearance to the lamp.

9 is a T-cock screw threaded into the wall of the neck 5 and having the horizontal passage 10 therethrough connecting with the receiving chamber 4, and the vertical opening 70 11 extending downwardly from said passage 10.

12 is a valve screw threaded into the outer end of the passage 10 and being for the purpose of regulating the supply of gas from 75 the receiving chamber 4 to the passage 11.

13 is a pipe having a cone shaped upper end 14 secured in the cup shaped opening 15 in the T-cock 9, said pipe extending downwardly for a considerable distance below 80 the mixing chamber 1 and having screw threaded to the lower end thereof the right angle hollow coupling 16.

17 is a valve cock having the central opening 18 therethrough and the screw threaded 85 opening 19 through the wall thereof adjacent to the lower end, said screw threaded opening 19 being engaged by the hollow coupling 16 and forming a passage for the gas into said central opening 18. 90

20 is a cap screw threaded onto the lower end of the valve cock 17 to facilitate the cleaning of the said valve cock and closing said lower end.

21 is a connecting nozzle screw threaded 95 at its lower end into the upper end of the valve cock 17 and at its upper end screw threaded into the lower end of the vertical pipe 22, said nozzle having a central opening therethrough corresponding in circum- 100

ference at its lower end to that of the opening 18 in the valve cock 17 and decreasing to a very small opening at its upper end.

23 is a funnel shaped tube screw threaded 5 at its upper end into the lower end of the mixing chamber 1 and joined at its lower end to the upper end of the pipe 22 and completing the passage from the receiving chamber 4 to the mixing chamber 1.

10 24 is a valve inserted in the valve cock 17 above the opening 19 and being for the purpose of shutting off the supply of gas to the mixing chamber 1, said valve having one of its ends slotted in ratchet formation 15 and being adapted to be operated by a ratchet lever 25 secured on said valve cock 17 so that when said lever is drawn down by means of the chain 26 secured thereto the valve will be opened or closed 20 according to its position before drawing down said lever.

27 is a valve screw threaded into the valve cock 17 above the valve 24 and being for the purpose of regulating the supply of 25 gas to the mixing chamber 1.

28 is a metal ring preferably having the outwardly flaring lower end 29 and being adjustably mounted on the pipe 22 adjacent to the lower end thereof and being 30 adapted to regulate the supply of air to the air slots 30 in said pipe 22.

31 is a wire gauze encircling the inner wall of the mixing chamber 1 and forming a lining for said chamber.

35 32 is a substantially dish shaped wire gauze adapted to rest on the upper end of the funnel shaped tube 23 between said tube and the gauze 31.

33 are pipes inserted in the openings 3 40 in the wall of the chamber 1 for the purpose of supplying gas to the burners 34.

35 is a T-cock screw threaded into the neck 5 and having the horizontal passage 36 therethrough connecting with the receiving chamber 4 and the vertical passage 37 extending downwardly from said passage 36.

38 is a valve closing the outer end of the passage 36 and regulating the supply of 50 gas to the passage 37.

39 is a pipe inserted in the passage 37 and leading downwardly adjacent to the upper ends of the burners 34 and having secured to the lower end thereof the curved 55 pipe 40, said pipe 40 having small burners 41 radiating therefrom to each of the large burners 34, the said burners 41 being always lighted so that when the gas is admitted to the burners 34 they will immediately become ignited by the flame from the smaller burners 41.

42 is a globe of substantially acorn shape mounted on the brackets 43 on the pipe 8 by means of the chains 44 and being adapted

to completely close in from the lower side 65 the lamp mechanism, said globe having the hole 45 through its apex for the insertion of the operating chain 26.

46 is a deflector mounted on the pipe 8 adjacent to the top of the globe 42 to prevent the heat or smoke from the burners 70 from discoloring the ceiling or bracket.

In the operation of this invention it will be seen that before the gas from the receiving chamber can reach the mixing chamber it must pass through the pipe 13 which is in close proximity to the burners 34 and as a consequence it becomes heated and by the time it reaches the said burners it is at the point of combustion. In its passage 75 through the heated pipe any impurities that may have been in the gas have been removed and consequently a bright and efficient light is given. The valve 24 affords a very simple and efficient means of turning 80 on or off the supply of gas to the mixing chamber as the ratchet is so arranged that one pull on the chain 26 will turn the valve a sufficient distance to open it while the next pull will turn the valve completely 85 around to its former position and close the passage again. A small quantity of the gas from the receiving chamber is continually flowing through the T-cock 35 to the small burners 41 and as these burners are 90 always lighted the larger burners 34 will become ignited simultaneously with the admittance of gas thereto thus providing a 95 convenient and efficient means of lighting the lamp.

What I claim is:—

1. In a gas lamp, a receiving chamber having an inlet connected to a gas supply and an outlet connected to a by-pass, said receiving chamber having an outlet, a mixing chamber partitioned from said receiving chamber and having a tubular lower extension, a screen lining and valve controlled air holes toward the lower end of said extension, a key valve in said extension having a ratchet control, a by-pass pipe connecting said receiving chamber with said extension, valves controlling said outlet from the receiving chamber, burners connected with said mixing chamber and in proximity to said by-pass pipe and pilot burners adjacent to the aforesaid burners and connected with the outlet from said receiving chamber.

2. In a gas lamp, a receiving chamber having an inlet connected to the gas supply, a mixing chamber partitioned from said receiving chamber and having a tubular lower extension, a screen lining in said mixing chamber, valve controlled air holes toward the lower end of said extension, a key valve in said extension having a ratchet control, a T-cock from said receiving chamber, a by-pass pipe extending downwardly from said

5 T-cock and connecting said receiving chamber with said extension, a valve in the outer end of said T-cock controlling the supply of gas from the receiving chamber to
 10 said by-pass pipe, burners connected with said mixing chamber and in proximity to said by-pass pipe and pilot burners adjacent to the aforesaid burners and connected with an outlet from said receiving chamber.

15 3. In a gas lamp, a receiving chamber having an inlet connected to the gas supply, a mixing chamber partitioned from said receiving chamber and having a tubular lower extension, a screen lining in said mixing chamber, valve controlled air holes toward the lower end of said extension, a nozzle screw threaded into the lower end of said extension, a valve cock secured to the lower end of said nozzle, a key valve in said 20 valve cock having a ratchet control, an operating chain secured to said ratchet control, a valve in said valve cock above said key valve controlling the supply of gas to said nozzle, a T-cock from said receiving chamber, a by-pass pipe extending downwardly from said T-cock and connected with said valve cock and connecting said receiving chamber with said mixing chamber, a valve in the outer end of said T-cock controlling the supply 25 of gas from the receiving chamber to said by-pass pipe, burners connected with said mixing chamber and in proximity to said by-pass pipe, pilot burners adjacent to the aforesaid burners and connected with an outlet from said receiving chamber and a globe closing in the whole from the lower end.

30 4. In a gas lamp, a receiving chamber having an inlet connected to the gas supply, a mixing chamber partitioned from said receiving chamber and having a tubular lower extension, a screen lining in said mixing chamber, valve controlled air holes toward the lower end of said extension, a nozzle screw threaded into the lower end of said extension, a valve cock secured to the lower end of said nozzle, a key valve in said valve cock having a ratchet control, an operating chain secured to said ratchet control, a valve 35 in said valve cock above said key valve controlling the supply of gas to said nozzle, a T-cock from said receiving chamber, a by-pass pipe extending downwardly from said T-cock and connected with said valve cock and connecting said receiving chamber with said mixing chamber, a valve in the outer end of said T-cock controlling the supply of gas from the receiving chamber to said by-pass pipe, burners connected with said mixing chamber and in proximity to said by-pass pipe, a T-cock secured in an outlet from said receiving chamber, a pipe extending downwardly therefrom and terminating adjacent to said burners, pilot burners from

40 said pipe adjacent to the aforesaid burners, a valve regulating the supply of gas to said pilot burners and a globe closing in the whole from the lower end. 65

45 5. In a gas lamp, a mixing chamber of substantially inverted cup shape, a receiving chamber formed by a cylindrical projection from the upper end of said mixing chamber, a supply pipe connecting said receiving chamber with the gas supply, an outlet from said receiving chamber, a T-cock secured in said outlet, a by-pass pipe extending downwardly from said T-cock and secured therein in a cone and cup connection, a valve in said T-cock regulating the supply of gas to said by-pass pipe, a screen lining in said mixing chamber, a cone shaped lower extension from said mixing chamber, a pipe secured in said extension and extending downwardly therefrom, air holes in said pipe adapted to be closed 50 by a valve adjustably secured on said pipe, a nozzle extending upwardly into said pipe, a valve-cock threaded onto the lower end of said nozzle and having a valve regulating the supply of gas to said nozzle, a key valve in said valve cock having a ratchet control, a chain secured to said ratchet for operating said key valve, a hollow coupling secured in an outlet adjacent to the lower end of said valve-cock and connecting said valve-cock 55 with said by-pass pipe and completing the passage for the gas from the receiving chamber to the mixing chamber, a cap closing in the lower end of said valve-cock and burners connected with said mixing chamber and 60 in proximity to said by-pass pipe.

6. In a gas lamp, a mixing chamber of substantially inverted cup shape, a receiving chamber formed by a cylindrical projection from the upper end of said mixing chamber, a supply pipe connecting said receiving chamber with the gas supply, an outlet from said receiving chamber, a T-cock secured in said outlet, a by-pass pipe extending downwardly from said T-cock and secured therein in a cone and cup connection, a valve in said T-cock regulating the supply of gas to said by-pass pipe, a screen lining in said mixing chamber, a cone shaped lower extension from said mixing chamber, a pipe secured in 65 said extension and extending downwardly therefrom, air holes in said pipe adapted to be closed by a valve adjustably secured on said pipe, a nozzle extending upwardly into said pipe, a valve-cock threaded onto the lower end of said nozzle and having a valve regulating the supply of gas to said nozzle, a key valve in said valve cock having a ratchet control, a chain secured to said ratchet for operating said key valve, a hollow coupling secured in an outlet adjacent to the lower end of said valve cock 70 and connecting said valve cock with said by-pass pipe.

4

pass pipe and completing the passage for the gas from the receiving chamber to the mixing chamber, a cap closing in the lower end of said valve cock, burners connected 5 with said mixing chamber and in proximity to said by-pass pipe, an outlet from said receiving chamber having a pipe extending downwardly therefrom adjacent to said burners, pilot burners from said pipe adjacent to the aforesaid burners, a valve in 10

said outlet regulating the supply of gas to said pilot burners, a globe of substantially acorn shape suitably mounted on the lamp stem and closing in the whole from the lower end, said globe having its apex pierced for 15 the insertion of the said chain, and a deflector mounted above said burners.

Signed at the city of Toronto, Ontario, this twenty-third day of July, 1915.

WILLIAM JESSE HENRY FULLER.
